UNITED STATES PATENT OFFICE.

MAX MAYER, OF NEW YORK, N. Y., ASSIGNEE TO M. J. WOHL & CO., INC., OF LONG ISLAND CITY, NEW YORK, A CORPORATION OF NEW YORK.

ARC-LIGHT CLUSTER.

1,409,191.

Specification of Letters Patent.

Patented Mar. 14, 1922.

Application filed November 20, 1920. Serial No. 425,431.

To all whom it may concern:

Be it known that I, MAX MAYER, a citizen of the United States, and residing in the city, county, and State of New York, have 5 invented certain new and useful Improvements in Arc-Light Clusters, of which the following is a specification.

This invention relates to improvements in electric arc light-clusters and especially to 10 that type commonly known as "top lights" in which the light of a suspended arc lamp is downwardly reflected and diffused by a transparent medium surrounding the lower part of the lamp, to provide uniform illumination of objects below the lamp, principally for photographic purposes.

It is the particular object of the present invention to provide a cluster of arc lamps which combines a maximum of evenly diffused light in a minimum of space.

It is another object of the invention to provide a top light cluster which is adapted to accommodate a plurality of arc lamps of standard design, lamps which also may be 25 used for horizontal projection or similar purposes, and to make these lamps instantly available for such different use.

It is a further object of the invention to provide a top light cluster which permits a 30 variation of light emission within a wide range, without special apparatus and with a minimum of current consumption.

With these and other objects in view the invention consists of a novel arrangement of 35 parts and details of construction hereinafter fully described and illustrated in the accompanying drawings, which form a part of these specifications and as finally pointed out in the claims.

On the drawings:

Fig. 1 is a sectional plan of the top arc light cluster on the line 1—1 of Fig. 2.

Fig. 2 is a front elevation of the cluster partly in section on the line 2—2 of Fig. 1.

Fig. 3 is a detail showing the hook 13 in elevation.

Fig. 4 is a detail sectional elevation through the diffuser 40.

Fig. 5 is a sectional plan on the line 5—5 of Fig. 4.

Fig. 6 is a detail elevation showing a central section of the top of reflector 30 in large scale,

Fig. 7 is a sectional detail of box 20 on the line 7—7 of Fig. 6.

55

Similar characters of reference indicate corresponding parts throughout the various views.

Referring to Fig. 2 of the drawings 1 is a central tube suitably suspended from the 60 ceiling of a room by means of a cap 2, insulating roller 3 and S shaped hook 4. On cap 2 is held by means of brackets 5 a horizontal rectangular frame consisting of parallel bars 6 and 7 which accommodate 4 65 pairs of two pulleys 8 turning freely on pins 9 in the open space between these bars. On each pair of pulleys a duplex arc lamp 10 is suspended by means of a rope or chain 11 and counterweight 12. The arc lamps 10 70 are fastened to rope 11 by means of a specially formed S hook 13 shown in detail in Fig. 3 provided with two complete rings of which the lower one accommodates the usual insulating roller and the upper one 75 remains free to permit the passing of the horizontal rods 14 therethrough. The inward ends of these rods are removably held in apertures of a collar 15 to which they may be fastened by screws 16, this collar 15 80 is slidably mounted on the central tube 1 to which it may be clamped by means of a hand screw 17. To the lower end of tube 1 a large reflector 30 forming the frustum of a cone is fastened by means of two nuts 18 and 19 85 whose threads engage the tube 1. The lower end of tube 1 holds by means of a male thread a box-like cap 20 provided with a central aperture (see detail shown in Figs. 6 and 7) through which a vertical rod 21 90 glides, the upper end of this rod is provided with a piston 22 to guide the rod within the tube 1 and to form a stop for the same. The lower end of rod 21 carries a diffuser 40 in form of an inverted cone, by means of nut 95 26 forming a knob for the rod 21. Rod 21 is also equipped with an angular pin 23, suitably placed, which may enter the cap 20 through slot 24 and be rotated in the same after entering, until the downwardly directed part of the pin drops into a suitable aperture 25 and locks the rod 21 in the cap 20. The reflector 30 is preferably made of sheet metal, its horizontal part is provided with four apertures through which the arc lamps 10 100 may enter from above, and consists of two

parallel circular plates 31 and 32, each aperture holds a short flanged vertical tube 33 whose horizontal flange is held in the space between the plates 31 and 32 and electrically welded thereto. The upper ends of tubes 33 are bent outwardly to form a rim 34 around each tube. The supporting plate 50 of the lamp mechanism rests in its lowest position upon the upper edge of tube 33 and the cylindrical lamp-housing 51 encircles this tube, centering screws 52 which are threaded in 51 engage the lower edge of rim 34 to hold the lamp mechanism in proper position on the reflector; plates 31 and 32 are provided with a number of ventilating apertures 37 which are covered by light shades 35. When lamps 10 are raised into the elevated position shown by dash and dotted lines of Fig. 2 the tubes 33 are closed by means of a cover 36. The conical side of reflector 30 is held between flanges of plates 31 and 32 and provided with four preferably hinged doors 38, in radial alinement with each lamp to facilitate trimming.

25 The conical diffuser 40 consists of two basket-like frames placed into each other and made of channel shaped moldings as shown in Figs. 4 and 5; 41 and 42 are cup shaped members which rest on nut 26. They 30 support the upright bars 43 arranged parallel to the surface of the diffuser cone and fitting into corresponding U shaped metal moldings 44.

The upper ends of each set of uprights 35 are joined by hoops 45 and 46 of the same cross section. Between the inner basket frame 41-43-45 and the outer frame 42-44-46 a sheet of woven glass fabric 49 is placed and the frames tied against each 40 other by means of screw 47 and the twisting of the wires 48 to clamp and stretch the glass fabric within the conical frames.

This arc light-cluster may be used to vary the illumination it provides within wide 45 limits, which is of particular value for photographic purposes. The arc lamps used therein are preferably duplex arc lamps having one mechanism for two arcs in series on a 125 volt circuit, a type which is in general 50 use in photographic studios as an illuminating unit. These lamps are easily fastened by means of hook 13 to the ropes 11 of the cluster and are then individually movable into and out of the reflector 30 providing 55 the rods 14 are removed from collar 15, the counterweights 12 holding the lamps balanced at any desired elevation. In this manner 2, 4, 6 or 8 arcs may be used simultaneously by providing a switch for each lamp. 60 The lamps not in use may be held above the reflector in the position shown in dotted lines in Fig. 2, where they can be lit to give a general illumination besides the specific one from the lamps in the reflector, or they may 65 be removed entirely and put to a different

use in the studio. By inserting the rods 14 through the rings of hook 13 into the collar 15 and fastening screws 16, two, three or four lamps can simultaneously be operated vertically and held in desired position by turning 70 hand screw 17. It may be remarked that the weight of the lamps is never carried by the reflector but entirely by the cap casting 2.

To reduce the cost of the cluster the counter balancing mechanism is sometimes 75 omitted in which case the lamps are hung directly on bars 14 and their weight held by means of collar 15 and screw 17 on the tube 1. The diffuser 40 can be moved vertically and held in its highest position by means of 80 pin 23 and cap 20 as heretofore described, it can be entirely removed from the cluster—if a strong direct illumination is desired—by unscrewing cap 20 from nut 19.

In this manner it is possible without the 85 use of dimming resistances or loss of current to vary the illumination from a dim diffused light—by using only one lamp and the diffuser—to an extremely strong direct light by using eight arcs within a single reflector 90 without the diffuser and such change can be effected in steps as well as almost instantaneously.

Having thus described my invention what I claim as new and desire to secure by Letters Patent is:

1. In a device of the kind described a central support adapted to be suspended on its upper end, a reflector held on the lower end thereof, a plurality of apertures in said reflector, arc lamps adapted to enter said apertures, an annular ring slidably mounted on said support and arms on said ring forming means for the suspension of said lamps.

2. In a device of the kind described, a central support adapted to be suspended on its upper end, a reflector surrounding said support attached near the lower end thereof, an annular ring slidably mounted on said support, a plurality of radial arms on said ring, arc lamps depending from said arms through apertures in said reflector, said arc lamps forming removable covers for said apertures.

3. In a device of the kind described, a 115 plurality of arc lamps surrounding a common support, said support having means adjustable to vary the vertical position of the lamps, a reflector in concentric alinement with said support, an aperture for each 120 lamp in said reflector permitting a part of said lamp to protrude into said reflector and means on each of said lamps for its central alinement within said aperture.

4. In a device of the kind described, a 125 diffusion screen consisting of a bowl shaped frame, being composed of a supporting hub, a ring held above said hub forming the circumference of said screen and channel shaped radial arms connecting said hub to 130

said ring, a sheet of translucent fabric on said frame and clamping means in the channels of said arms to fasten said fabric to said frame.

- 5 5. In a device of the kind described, a central tube surrounded by a plurality of lamps, a reflector above said lamps, a cap on said tube to support said reflector, a rod holding a diffuser at its lower end slidably and rotatively mounted in said tube, a pin on said rod adapted to enter said cap forming means to support and to lock said diffuser in elevated position by a rotative movement of said diffuser without access to the interior 15 portion thereof.

6. In a device of the kind described, a diffusing screen consisting of two similar bowl shaped frames fitting into each other, each frame being composed of a supporting hub 20 and a ring held above said hub forming the circumference of said screen, and radial arms connecting each hub to its ring, a sheet of translucent fabric inserted between said frames and means to clamp said frames 25 against each other to hold said sheet.

7. In a device of the kind described, a central support adapted to be suspended on its upper end a plurality of arc lamps movably attached to said support, a reflector surrounding said support provided with apertures permitting said lamps to enter said reflector and separate counterbalancing means for each arc lamp to hold all of said lamps at different elevations.

- 35 8. In a device of the kind described, a central support adapted to be suspended on its upper end a plurality of arc lamps movably attached to said support, a reflector surrounding said support provided with apertures permitting said lamps to protrude into said reflector, counterbalancing means for said arc lamps, and means to hold all of said lamps at the same elevation and in balanced condition.

- 45 9. In a device of the kind described, a central support adapted to be suspended on its upper end, a plurality of arc lamps movably attached to said support, a reflector surrounding said support provided with apertures permitting said lamps to protrude into said reflector, counterbalancing means for said arc lamps and means to move a number

of said lamps simultaneously and permitting to move other lamps singly in balanced condition.

55

10. In a device of the kind described, a central support adapted to be suspended on its upper end, a reflector and a diffusing screen concentrically held by said support, a plurality of arc lights arranged in pairs 60 enclosed by said reflector and said screen, means to permit the removal of each pair of lights separately from said reflector and means on said support to hold said lights in elevated position above said reflector.

65

11. In a device of the kind described, the combination with a reflector adapted for ceiling suspension and provided with a plurality of apertures surrounding a common center; of lamps adapted to enter said apertures, supporting means above said reflector to hold said lamps in alinement with said apertures, and means to vary the vertical position of said lamps.

70

12. In a device of the kind described, the combination with a reflector adapted for ceiling suspension and provided with a plurality of apertures surrounding a common center; of lamps adapted to enter said apertures, supporting means above said reflector 80 to hold said lamps in alinement with said apertures, and counterbalancing means to vary the vertical position of said lamps.

75

13. In a device of the kind described, the combination with a reflector adapted for 85 ceiling suspension and provided with a plurality of apertures surrounding a common center; of lamps adapted to enter said apertures, supporting means above said reflector to hold said lamps in alinement with said 90 apertures, means to vary the vertical position of said lamps and means to hold all of said lamps in horizontal alinement.

14. In a device of the kind described, the combination with a reflector adapted for 95 ceiling suspension and provided with a plurality of apertures surrounding a common center; of lamps in alinement with said apertures, means to hold some of said lamps at the same vertical elevation and means permitting a variation of the vertical position 100 of one or more other lamps.

MAX MAYER.
